SPEED GOVERNOR

Theophile Tarisien, Livry-Gargan, France, assignor to The Westinghouse Air Brake Company, Wilmerding, Pa., a corporation of Pennsylvania

Original application January 8, 1935, Serial No. 809. Divided and this application July 12, 1935, Serial No. 31,044. In France April 11, 1934

14 Claims. (Cl. 137—140)

This invention relates to speed governors and more particularly to a speed controlled valve device, the present application being a division of my pending application, Serial No. 809, filed January 8, 1935, and now Patent No. 2,061,883 issued Nov. 24, 1936.

The principal object of the invention is to provide an improved valve device of the above type.

10 In the accompanying drawing; Fig. 1 is a sectional view of a speed controlled valve device constructed in accordance with my invention; and Fig. 2 is an end view of the device shown in Fig. 1 with the cover removed.

15 As shown in the drawing, the speed controlled valve device comprises a body or casing 16 having a chamber 17 which is open at one end, the open end of chamber 17 being closed by a cover 15. A pipe 18 is connected to the cover 15 and communicates through a passage 14 with chamber 17.

20 A rotor 19 is disposed in the chamber 17 and is mounted upon one end of a shaft 20 which extends through the closed end wall of chamber 17, said shaft being carried by suitable ball bearings 21 provided in the casing 16. The shaft 20 extends beyond the exterior surface of the casing 16, and any suitable driving means such as a pulley 22 is secured to the outer end of 25 said shaft through the medium of which said shaft is adapted to be rotated.

25 The inner face of the rotor 19 abuts and slidably seals against an annular bearing plate 23 inset in the inner end wall of chamber 17, the plate 23 being provided with a port 24 leading to a passage 25 which communicates with a pipe 26 connected to the casing 16. The face of the rotor 19 in contact with the bearing plate 23 is provided with an annular cavity 27 communicating with a port 28 leading to the opposite or outer face 29 of the rotor 19 which is also provided with an axial port 30 which communicates with an outlet passage 31 in the casing through an axial bore 13 in the shaft 20, and a radial bore 12 which opens at one end to the bore 13 and at the other end to an annular cavity 11 which is provided in the casing around said shaft and which is open to the passage 31.

30 A radially disposed valve seat 29 is provided on the outer face of the rotor 19 between two spaced parallel guides 77, and a slide valve 33 is mounted to slide on said seat between said guides. The slide valve 33 is resiliently held in contact with the seat 29 by means of a spring 34 mounted on a segmental member or mass 35

which is rigidly secured to the guides 77. A slider 36 is disposed between the guides 77 at one end of the slide valve 33 and is adapted to engage said slide valve for moving same in one direction on the seat 29. The slider is provided in one end with a bore which receives a pin 10 secured in the slide valve through the medium of which the slide valve is adapted to be pulled in the opposite direction. The pin 10 fits loosely in the bore in the slider 36 so as to provide a certain amount of play between the slide valve and slider.

35 A movable segmental member or mass 37, similar to the rigid member 35, is secured to the slider 36 for moving the slide valve 33 according to the speed of rotation of the rotor 19. This member 37 is slidably mounted in a space formed between the outer surface of the guides 77 and two guide plates 32 which are secured to central raised portions 78 of the guides 77, engagement 40 of said member with said raised portions being adapted to limit inward movement of said member and thereby the slide valve 33.

45 A compression spring 38 is interposed between the slider 36 and an upstanding abutment 39 secured to the rotor 19 and acts to urge the slider 36, the slide valve 33 and the member or mass 37 to their radially inward position as shown in the drawing.

50 The slide valve 33 is provided with a cavity 40 which in the position of the parts shown in the drawing is adapted to establish communication between the ports 28 and 30. The slide valve is movable on the seat 29 to another position in which the above communication is closed and port 28 is open to chamber 17.

55 In operation, with the rotor at rest, the pipe 26 is connected by way of passage 25, port 24 in the plate 23, annular cavity 27, port 28, cavity 40 in the slide valve 33, ports 30, 13 and 12, and 40 the annular cavity 11 to passage 31.

60 When the rotor 19 is rotated by the pulley 22 through the medium of shaft 20, the action of centrifugal force on the member 37 opposes the action of spring 38, and when the speed of the 45 rotor becomes sufficiently great, the member 37 gradually moves outwardly compressing the spring 38. This movement of the member 37 acting through the slider 36 shifts the slide valve 33 on its seat until by the time a certain 50 speed of rotation of rotor 19 is obtained, the port 28 is uncovered by the end of said slide valve and opened to chamber 17 thereby establishing communication from pipe 18 to pipe 26 through said chamber and port, the annular 55

cavity 27, port 24 and passage 25. It will be noted that in this position of the slide valve 33 the cavity 40 is moved out of registry with port 28.

5 As the speed of the rotor 19 is decreased, the action of centrifugal force on the member 37 reduces, which permits the spring 38 to gradually return the slide valve 33 to the position in which cavity 40 connects passages 28 and 30, and 10 communication between passage 28 and chamber 17 is closed.

The mass 35 which is fixed to the rotor 19 is provided to substantially counteract or neutralize the action of centrifugal force on the movable mass 37 during operation of the governor.

It should be noted that the slide valve 33 occupies a plurality of various positions according to the speed of rotation of the rotor 19 and may, if desired, be arranged to control in said positions 20 a greater or less number of communications, than above described, without exceeding the scope of the invention.

While one illustrative embodiment of the invention has been described in detail, it is not my 25 intention to limit its scope to that embodiment or otherwise than by the scope of the appended claims.

Having now described my invention, what I 30 claim as new and desire to secure by Letters Patent, is:

1. A speed governor for controlling flow of fluid under pressure comprising a casing, a rotor carried by and mounted to rotate in said casing and having on one face a slide valve seat and 35 having a fluid conducting passage opening into said seat, a valve mounted to slide on said seat for controlling communication to said passage, resilient means acting on said slide valve pressing same into engagement with said seat, a member 40 carried by said rotor and connected to said slide valve and operative by centrifugal force due to rotation of said rotor for shifting said slide valve on its seat, and spring means carried by said rotor acting on said member in opposition to the action 45 of centrifugal force on said member.

2. A speed governor for controlling flow of fluid under pressure comprising a casing, a rotor carried by and mounted to rotate in said casing and having a slide valve seat and a fluid conducting 50 passage opening into said seat, a valve mounted to slide on said seat for controlling communication to said passage, means for maintaining said valve in engagement with said seat, a member carried by and mounted to slide radially on said 55 rotor and operative by centrifugal force due to rotation of said rotor for shifting said slide valve on its seat, and spring means carried by said rotor acting on said member in opposition to the action of centrifugal force on said member.

60 3. A speed governor for controlling flow of fluid under pressure comprising a casing, a rotor carried by and mounted to rotate in said casing and having on one face a flat slide valve seat and 65 having a passage opening into said seat, a valve mounted to slide radially on said seat for controlling communication to said passage, means for maintaining said valve in contact with said seat, a member carried by and mounted to slide radially on said rotor and operative by centrifugal 70 force due to rotation of said rotor for shifting said slide valve on its seat, and spring means carried by said rotor acting on said member in opposition to the action of centrifugal force on said member.

75 4. A speed governor for controlling flow of fluid

under pressure comprising a casing having a chamber, a rotor carried by said casing and disposed in said chamber with one face in rotary sealing engagement with one side wall of said chamber, said rotor having on the opposite face a slide valve seat and having a passage opening to said seat and communicating with a passage in the side wall of the casing with which said rotor is in sealing engagement, a valve mounted to slide on said seat for controlling communication through said passage, a member carried by said rotor and operative by centrifugal force according to the speed of rotation of said rotor for shifting said slide valve on said seat, and spring means carried by said rotor and acting on said member to control movement of said member by centrifugal force.

5. A speed governor comprising a casing, a rotor mounted to rotate in said casing, means for turning said rotor, said rotor having a slide valve seat and a fluid conducting port opening at said seat, a slide valve mounted to slide on said seat and movable to various positions for controlling communication through said port, means acting to press said slide valve against said seat, a spring carried by said rotor operative to urge said slide valve in one direction on its seat, a member carried by said rotor and movable relatively thereto under the action of centrifugal force to shift said slide valve against said spring to a position depending upon the speed of rotation of said rotor, and means connecting said member to said slide valve.

6. A speed governor comprising a casing, a rotor mounted to rotate in said casing, means for turning said rotor, said rotor having a flat slide valve seat and a fluid conducting port opening at said seat, a slide valve mounted on said seat and movable radially to various positions for controlling communication through said port, means for maintaining said slide valve in contact with said seat, a spring carried by said rotor operative to urge said slide valve in one direction on its seat, and a member carried by said rotor and movable relatively thereto under the action of centrifugal force to shift said slide valve against said spring to a position depending upon the speed of rotation of said rotor.

7. A speed governor comprising a casing, a rotor mounted to rotate in said casing, means for turning said rotor, said rotor having on one end a slide valve seat and a fluid conducting port opening at said seat, a slide valve mounted on said seat and movable to various positions for controlling communication through said port, a spring carried by said rotor operative to urge said slide valve in one direction on its seat, a member carried by said rotor and movable relatively thereto under the action of centrifugal force to shift said slide valve against said spring to a position depending upon the speed of rotation of said rotor, means connecting said member to said slide valve, and means for moving said slide valve relative to said member into engagement with said seat and for urging said slide valve against said seat.

8. A speed governor comprising a casing, a rotor mounted to rotate in said casing, means for turning said rotor, said rotor having on one end a flat slide valve seat and a fluid conducting port opening at said seat, a slide valve mounted on said seat and movable radially to various positions for controlling communication through said port, means for maintaining said slide valve in contact with said seat, a spring carried by said

5 rotor operative to urge said slide valve in one direction on its seat, and a member carried by said rotor and movable relatively thereto under the action of centrifugal force to shift and slide valve against said spring to a position depending upon the speed of rotation of said rotor.

9. A speed governor comprising a casing having a chamber, a rotor disposed in said chamber in sliding contact with a portion of said casing, said casing and rotor having means coacting at the contacting surfaces to establish a fluid pressure conduit from a passageway in said casing to a port in said rotor, said rotor having a slide valve seat at which said port opens, a slide valve mounted on said seat and operative to control communication through said port, a spring carried by said rotor and acting on said slide valve for urging said slide valve on said seat in one direction, and a member carried by and movable relatively to said rotor under the action of centrifugal force to shift said slide valve in the opposite direction a distance depending upon the speed of rotation of said rotor.

10. A speed governor comprising a casing having a chamber, a shaft mounted in said casing and extending into said chamber and adapted to be rotated, a rotor disposed in said chamber and secured to said shaft for rotation therewith, one end of said rotor having sliding contact with an end wall of said chamber, said rotor having a passage, said end of said rotor and the contacted end wall of said chamber having coacting means for establishing a fluid conduit from a passageway in said casing to said passage in said rotor throughout full rotative movement of said rotor, said rotor having a slide valve seat at which said passage opens, a slide valve mounted on said seat and movable to various positions for controlling communication through said passage, a spring carried by said rotor and acting on said slide valve for urging said slide valve on said seat in one direction, and a member carried by and movable relative to said rotor under the action of centrifugal force to shift said valve in the opposite direction a distance which varies according to the speed of rotation of said shaft and thereby said rotor.

11. A speed governor comprising a casing having a chamber, a rotor disposed in said chamber in sliding contact with a portion of said casing, said casing and rotor having means coacting at the contacting surfaces to establish a fluid pressure conduit from a passageway in said casing to a port in said rotor, said rotor having a slide valve seat at which said port opens, an axial passage extending through a portion of said shaft and through said rotor and opening at said slide valve seat, a slide valve mounted on said seat and movable to various positions for controlling communication through said passages, a spring 50 for urging said slide valve in one direction on said seat, and a member carried by and movable relatively to said rotor under the action of centrifugal force to shift said valve in the opposite

direction a distance which varies according to the speed of rotation of said shaft and thereby said rotor.

12. A speed governor comprising a casing having a chamber, a shaft carried by said casing and extending into said chamber, a rotor mounted on said shaft within said chamber and having one face in sliding contact with the casing wall within said chamber and having a slide valve seat, said casing and rotor having means coacting at the sliding contacting surfaces for establishing communication from a passageway in said casing to a passage in said rotor through full turning movement of said rotor relative to said casing, an axial passageway extending through said shaft and open at one end to a passage in said rotor, said passages opening at said valve seat, a slide valve mounted on said seat and movable to various positions on said seat for controlling communication between said passages, and one of said passages and said chamber, a spring for urging said slide valve in one direction on said seat, and a member carried by and movable relatively to said rotor under the action of centrifugal force for moving said slide valve in the opposite direction a distance which varies according to the speed of rotation of said shaft and thereby said rotor.

13. A speed governor comprising a casing, a rotor mounted to rotate in said casing and having an end face and a slide valve seat formed radially on said face, a guide on each side of said valve seat, a slide valve mounted to slide on said seat between said guides, a spring associated with said rotor and acting on said slide valve urging said slide valve to its seat, an actuator disposed between said guides and operatively connected to said slide valve, a spring carried by said rotor and acting on said actuator for urging said slide valve in one direction, a member mounted to slide with one face on said guides and secured to said means and movable relatively to said rotor under the action of centrifugal force for moving said slide valve in the opposite direction a distance which varies according to the speed of rotation of said rotor, and means associated with said rotor and extending over the opposite face of said member and coacting with said guides to maintain said actuator and member in operative relation with said slide valve.

14. A speed governor for controlling the flow of fluid under pressure comprising a casing, a rotor carried by and mounted to rotate in said casing and having a slide valve seat, a slide valve mounted on said seat and urged into contact with said seat, a member carried by said rotor and movable by centrifugal force upon rotation of said rotor, a spring acting on said member for opposing movement thereof by centrifugal force, and means connecting said member to said slide valve for moving said slide valve with said member.

THEOPHILE TARISIEN.

CERTIFICATE OF CORRECTION.

Patent No. 2,081,466.

May 25, 1937.

THEOPHILE TARISIEN.

It is hereby certified that error appears in the printed specification of the above numbered patent requiring correction as follows: Page 3, first column, line 4, claim 8, for the word "and" read said; and that the said Letters Patent should be read with this correction therein that the same may conform to the record of the case in the Patent Office.

Signed and sealed this 27th day of July, A. D. 1937.

Henry Van Arsdale

(Seal)

Acting Commissioner of Patents.
